FIG. 5.

UNITED STATES PATENT OFFICE.

CHARLES C. BENDER AND JAMES E. FISH, OF BLOOMINGTON, INDIANA.

PROVISION-SAFE.

SPECIFICATION forming part of Letters Patent No. 752,509, dated February 16, 1904.

Application filed September 12, 1903. Serial No. 172,957. (No model.)

To all whom it may concern:

Be it known that we, CHARLES C. BENDER and JAMES E. FISH, citizens of the United States, residing at Bloomington, in the county of Monroe and State of Indiana, have invented new and useful Improvements in Provision-Safes, of which the following is a specification.

Our invention relates to new and useful improvements in provision-safes for butter, cheese, &c.; and its object is to provide a stand having a counterbalanced cover which is adapted to be held in position over the cheese or butter and which can be readily removed therefrom and held suspended thereabove.

A further object is to provide means for locking the cover after it has been lowered into position over the butter, cheese, &c., therewith, so as to prevent it from being raised by the action of the counterweight.

With the above and other objects, in view the invention consists in the novel construction and combination of parts hereinafter more fully described and, claimed, and illustrated in the accompanying drawings, showing the preferred form of our invention, and in which—

Figure 1 is a perspective view of our improved provision-safe. Fig. 2 is an enlarged perspective view of a portion of one of the standards and showing the rope-securing slide, a portion of the standard and slide being shown in section. Fig. 3 is a section on line 3 3, Fig. 2. Fig. 4 is a vertical section through a portion of the cross-bar upon the standards, and Fig. 5 is a detail view of the cover-attaching means.

Referring to the figures by numerals of reference, 1 is a platform having standards 2 and 3 arranged thereon, the standard 3 being provided in one face with a longitudinally-extending groove 4. A cross-bar 5 is secured upon standards 2 and 3 and has a passage 6 extending longitudinally therethrough from the groove 4 in standard 3 to the center of the cross-bar, and within this passage are journaled pulleys 7. The side walls of the groove 4 are recessed for the reception of flanges 8, extending from the sides of a slide 9, arranged within the groove 4, and the outer

face of this slide has a handle 10, whereby it may be readily manipulated. A plunger 11 extends transversely through the handle 10 and the slide 9 and projects into a recess 24, formed in the inner face of the slide 9. A spring-catch 25, preferably formed of a strip of material having an inwardly-extending projection 26, is secured at one end to the rear wall of the groove 4, and the inwardly-projecting end thereof is slidably mounted in a recess 27, formed in the rear wall of said groove. The upper or free end of the spring-strip 25 normally projects from the inner wall of groove 4, and the projection 26 forms a stop for the purpose hereinafter more fully described. A cord 13 is fastened to the upper end of the slide 9 and extends over the pulleys 7 and over the passage 6 and thence downward from the center of the cross-bar 5. A yoke 14 is fastened to the end of the cord 13 and is connected to a nut 15, which engages the screw-threaded stem 16 of a snap-hook 17. A flexible cord 18 is secured to the lower end of the slide 9 and extends through the platform 1 and is provided with a counterbalance 19. A cover 20, preferably formed of glass, is arranged on the platform between the standards and has a ring 21 connected to the center of the top thereof, and this ring is adapted to be engaged by the snap-hook 17.

The cheese or other material to be covered is placed upon the platform with the cover 20 in position thereover, and when it is desired to cover the cheese the handle 10 is grasped and the slide 9 is pressed upward, thereby causing the spring-strip 25 to be pressed backward against the inner wall of groove 4 and moving the extension 26 backward into the recess 27. Simultaneously with the arrival of the cover 20 upon the platform 1 the recess 24 in slide 9 comes into position over the free end of strip 25, and said end promptly swings outward into the recess and locks the slide against downward movement. If the cord 13 should contract or expand, the exact distance from the locked slide to the cover can be covered by screwing the stem 16 downward or upward within the nut 15. The locking-strip 25 prevents accidental raising of the cover 20, and in order to raise said cover it is

first necessary to depress the plunger 11, so as to force the projecting end of said strip into the recess 27 and out of the recess 24. The slide can then be moved downward by grasping the handle 10 thereof, and this downward movement will raise the cover. As the weight 19 is equal to the weight of cover 20, it is obvious that said cover will be automatically held in any position to which it may be adjusted. The slide and its operating mechanism are located at the back of the device and out of reach of persons who are not authorized to remove the cover from its lowered position. The catch in the slide serves to support the weight of the counterbalance 19, and thereby permits the cover 20 to rest firmly on the platform.

It will be seen that the device is extremely simple in construction and will form an attractive article of furniture for use in stores.

Any desired means may be provided for permitting the ventilation of the cover when the same is in position upon the platform. We preferably provide apertures 22 within the platform, (shown by dotted lines in Fig. 1,) said apertures communicating with the grooves extending along the lower surface of the platform and indicated by the numeral 23.

In the foregoing description we have shown the preferred form of our invention; but we do not limit ourselves thereto, as we are aware that modifications may be made therein without departing from the spirit or sacrificing any of the advantages thereof, and we therefore reserve the right to make such changes as fairly fall within the scope of our invention.

Having thus described the invention, what is claimed as new is—

1. The combination with a platform having standards thereon and a cross-bar on the standards; of a slide mounted on one of the standards, a cord connected to the slide and depending from the cross-bar, a cover adjustably connected to and supported by the cord, and a counterbalance connected to the slide.

2. The combination with a platform having standards thereon, and a cross-bar on the stand-

ards; of a slide mounted upon one of the standards, means for locking the slide in adjusted position, a cord connected to the slide and depending from the cross-bar, a cover adjustably connected to said cord and supported thereby, and a counterbalance connected to the slide.

3. The combination with a platform; of a grooved standard thereon, a cross-bar mounted upon the standard, a slide upon the standard, means for locking the slide against downward movement within the standard, a plunger on the slide adapted to release the slide from the locking means, a cord secured to the slide and depending from the cross-bar, a cover adjustably connected to and supported by said cord, and a counterbalance connected to the slide.

4. The combination with a platform; of a longitudinally-grooved standard thereon, a cross-bar upon the standard, a slide within the groove in the standard, a handle thereon, a spring within the groove and adapted to engage the slide, a plunger mounted within the slide for releasing the spring from the slide, a cord connected to the slide and arranged within the groove and cross-bar, a cover adjustably connected to and supported by said cord, and a counterbalance suspended from the slide.

5. The combination with a platform; of standards thereon, a cross-bar connecting the standards, a cord mounted within the cross-bar and one of the standards, a weighted recessed slide mounted on one of the standards and connected to said cord, a cover adjustably connected to and supported by the cord, a spring upon the standard adapted to engage the slide, and means for removing the spring from engagement with the slide.

In testimony whereof we affix our signatures in presence of two witnesses.

CHARLES C. BENDER.
JAMES E. FISH.
